UNITED STATES PATENT OFFICE

2,125,906

ARTIFICIAL CHRISTMAS TREE

John Frei, Jr., Chicago, Ill., assignor to The Glolite Corporation, Chicago, Ill., a corporation of Illinois

Application April 8, 1936, Serial No. 73,206

4 Claims. (Cl. 240—10)

My invention relates to Christmas trees.

Broadly, the present invention may be characterized as an improvement over the illuminated artificial plant shown in my Patent No. 1,921,614, granted August 8, 1933.

More specifically, the invention consists in certain novel combinations and arrangements of parts, as will hereinafter be more fully set forth and claimed.

10 In describing this invention, reference is had to the accompanying drawings wherein I have illustrated the preferred physical embodiments of my invention, and in which—

15 Figure 1 is a front elevational view of a Christmas tree embodying the principles of the present invention;

Figure 2 is an enlarged fragmentary view, partly in front elevation and partly in vertical section, of the device of Figure 1;

20 Figures 3, 4 and 5 are detail views of the means and certain of the steps in the method of securing light transmitting elements to the device of Figures 1 and 2;

Figure 6 is a fragmentary elevational view of 25 the foliage adapted to be employed in connection with the device of Figure 2.

Referring now in detail to Figures 1 to 5, inclusive, of the drawings, the Christmas tree of the present invention comprises a base 10 which, except as hereinafter provided, may be of any suitable or preferred form. In the form shown in the drawings, the base is circular in configuration and it is preferably formed from substantially opaque and non-heat conducting material, such as porcelain or a quick-setting plaster, although it may be formed of any other suitable or preferred material. This base is adapted to support a suitable source of light such, for example, as the electric light bulb 11, the bulb being received in a suitable socket (not shown) in the base. The bulb projects above the base and is supplied with current through the medium of electric cord 12.

In addition to supporting bulb 11, the base also supports a suitable light-confining hood 13. This hood, in the broader aspects of the invention, may be of any suitable or preferred form. However, as the physical embodiment of the instant invention is shown as a Christmas tree, the hood is, therefore, cone-shaped. Preferably the hood is formed of opaque material, such as relatively heavy cardboard, although any other suitable material, opaque, translucent, or transparent, may be employed. As shown, the lower open end 55 of the hood seats on the base, and with sides 14

of supporting surface 15 of the base in contact with the inner surface of the wall of the hood. Sides 14 of the base are preferably inclined upwardly and inwardly to conform with the upwardly and inwardly inclined wall of the hood. 5 This permits of a wedging action between the hood and the base to position firmly the hood thereon. Vent openings 16 formed in base 10, and vent openings 17 formed in hood 13, permit free circulation of air through chamber 18 formed by the hood and base, to thereby dissipate the heat from the light source.

Hood 13 is also provided with a plurality of bores 19 for the reception of light transmitting elements in the form of glass rods 20. At one end these rods have a relatively snug fit in their respective bores 19, and they project for a relatively short distance into chamber 18, being thereby placed in light-conducting communication with light source 11. From such chamber 20 the rods project outwardly from, and are inclined upwardly with respect to, the hood, and each terminates in an object to be illuminated. As shown, the rods projecting from the side wall of the hood are each provided with a pear-shaped object 21, simulating the flame of a candle, while the rod projecting axially from the top of the hood is provided with a star-shaped object 22. This star-shaped object is preferably formed on the rod in the manner set out in my co-pending application, Serial No. 73,208, filed April 8, 1936, for Light transmitting element and method. Also, certain of the rods preferably have that portion thereof which projects into chamber 18 colored, as indicated at 23, in the manner and for the purpose set out in my co-pending application, Serial No. 55,174, filed December 19, 1935, for Colored ornamental light and method. When bulb 11 is illuminated, the light rays emanating therefrom will pass through the rods 20 and illuminate the objects at the outer ends thereof. 40

If desired, dependence may be placed upon the relatively snug fit of the rods in their respective bores to secure the rods to the hood. It is preferred, however, to provide additional means to 45 rigidly secure and brace the rods on the hood. Such means comprises a tube 25, preferably formed of an opaque material, such as relatively heavy cardboard. Any other suitable material, opaque, translucent or transparent, may be employed. The diameter of the tube is such that rod 20 has a relatively snug fit therein, and it has a length appreciably less than the length of the rod. When the rod and tube are in position with respect to the hood, the tube em- 50 55

braces the rod with its outer end abutting the object 21 of the rod, and with its inner end disposed in abutting contact with the outer surface of the hood. An adhesive serves to bind the tube 5 to the hood. Any suitable adhesive may be employed. I preferably, however, use tar, which may be applied in the manner shown in Figures 3 to 5, inclusive. To practice such method, I first take a rod and tube and insert the rod into the tube until its forward end abuts the object 21. The opposite projecting end of the rod, closely adjacent the end of the tube, is then held in contact with a tar wheel 26. This tar wheel may be supported and rotated in a tank 27 in any suitable or preferred manner, the tank being adapted to contain a quantity of tar 28 therein, which tar is maintained in a fluid or plastic condition by heat applied to tank 27 through the medium of burner 29. Rotation of the tar wheel will cause 10 a ring of tar to be collected on a rod held in contact therewith and, when a sufficient quantity of tar has been collected on the rod, the exposed end of the rod is then inserted into its bore in the hood until the inner end of the tube contacts the outer surface of the hood. This will cause a collar of tar 28', which is still in a plastic condition, to be formed about tube 25, such collar also being disposed in contact with the outer surface of the hood. When the tar solidifies, upon 15 cooling, it will effectively adhere to both the tube and the hood, and thereby rigidly secure the tube thereto. Formation of collar 28' by insertion of rod 20 into its bore in the hood will also cause a quantity of tar to be squeezed between the rod 20 and the tube, thereby effectively securing the tube directly to the rod. The tube, being held rigid with respect to the hood, constitutes a reinforcement or bracing means for the rod. It may here be stated that rod 20a, which supports 20 object 22, is connected to the hood in a slightly different manner. In this case, the tube 25a merely seats on a washer 31 disposed between the tube and the upper marginal edge 32 of the hood. This washer may be formed of cork, or any 25 other suitable resilient material. Rod 20a is preferably of considerably greater length than rods 20, and it extends into hood 13 for an appreciable distance. To properly brace the rod, therefore, a second washer, or annular member 33, is disposed internally of the hood and connected thereto as by a suitable adhesive 34. This washer may also conveniently be formed of cork, and it has a relatively tight fit with rod 20a, which it embraces. While no adhesive is 30 employed between the washer 31 and the hood 13 and tube 25a, such washer could, of course, be cemented to both the hood and tube, if desired. Hood 13, in addition to its functions of supporting rods 20 in light conducting communication with light source 11, and confining the rays of light emanating from such source, also constitutes the body of the tree, while the rods 20 and tubes 25, in addition to their functions as light transmitting elements and bracing means, 35 respectively, form, in effect, the branches of the tree. Both the hood 13 and tubes 25 are wrapped with a suitable material, known commercially as "Visca", to simulate the foliage of the tree. As shown in Figure 6, this "Visca" is composed of 40 relatively thin and narrow strips of paper 35 which are confined, substantially centrally of their length, between a pair of braided wires 36. In wrapping the "Visca" about the hood and tubes, a length of the material is first laid axially 45 along the upper portion of the hood and along

the entire length of tube 25a, as indicated at 5 37. The material is then wrapped about the tube, in a downward direction from object 22, as indicated at 38, and over the length of material 37 to thereby anchor such length of material below wrapping 38. The material is then wrapped about hood 13 until the first tube 25 is reached, at which point it is wrapped about tube 25 from the inner end to the outer end thereof, from whence it is again returned to the hood. The 10 remainder of the hood, and each of the tubes, is wound with the material in a like manner. The material extends around the hood to a point closely adjacent the marginal edge 40 thereof. From such point, the free end of the material is 15 returned to one of the lowermost tubes 25. It will be apparent that, as the material extends from the outer end of tube 25 to the hood, the portion of material 41 between such points will be spaced slightly from the hood. The free end 20 of the material returned to the lowermost tube is, therefore, passed upwardly through such space, then around tube 25, and thence back to the portion 41 of the material about which it is wrapped. This anchors the lower free end of the material. 25

While the rods 20 are conveniently formed of glass, any other material suitable for the purpose and capable of producing the desired results, may be employed. It will be understood, therefore, 30 that the term "glass", as used herein, is to be construed as meaning either glass proper or any other material equivalent to glass within the teaching of my invention as defined in the appended claims. 35

Further, although preferred embodiments of 40 my invention have been illustrated and described, by way of example, it will be obvious that changes may be made therein within the spirit and scope of the invention, and, therefore, I do not limit my invention to the forms thereof herein disclosed, except insofar as it may be so limited in the appended claims. 45

What I claim is:

1. An illuminated artificial Christmas tree comprising in combination a hollow form in substantially the desired shape of the tree and constituting the body of the tree, a light source supported within said form, a plurality of elongated light transmitting elements associated with said form, each of said elements having one end disposed in light conducting relationship with said light source and having an object to be illuminated at the opposite end thereof, a relatively opaque rigid tube enclosing each of said light transmitting elements and having one end abutting said object and the opposite end terminating exteriorly of and abutting said form, said tubes supporting said light transmitting elements upon said form and confining therein the rays of light passing therethrough to said object, and means securing said tubes to said form. 50

2. An illuminated artificial Christmas tree comprising in combination a hollow form in substantially the desired shape of the tree and constituting the body of the tree, a light source supported within said form, a plurality of light transmitting elements comprising glass rods associated with said form, each of said rods having one end disposed in light conducting relationship with said light source and having an object to be illuminated at the opposite end thereof, an opaque rigid tube enclosing each of said rods and having contact therewith for the full length of said rod, said tubes having one end abutting the object on said 55 60 65 70 75 80 85 90 95 100

rod and the opposite end terminating exteriorly of and abutting said form, and said tubes supporting said light transmitting elements upon said form and confining therein the rays of light passing therethrough to said object, and means securing said tubes to said form.

3. An illuminated artificial Christmas tree comprising in combination a hollow form in substantially the desired shape of the tree and constituting the body of the tree, a light source supported within said form, a plurality of light transmitting elements comprising glass rods associated with said form, each of said rods having one end disposed in light conducting relationship with said light source, and having an object to be illuminated at the opposite end thereof, an opaque rigid tube enclosing each of said rods and having contact therewith for the full length of said rod, said tubes having one end abutting the object on said rod and the opposite end terminating exteriorly of and abutting said form, and said tubes supporting said light transmitting elements upon

said form and confining therein the rays of light passing therethrough to said object, and a collar of adhesive material carried by and embracing said tubes and securing said tubes to said form.

4. An illuminated artificial Christmas tree comprising, in combination, a hollow form in substantially the desired shape of the tree and constituting the body of the tree, a light source supported within said form, a plurality of elongated light transmitting elements associated with said form, each of said elements having one end disposed in light conducting relationship with said light source and having an object to be illuminated at the opposite end thereof, an elongated relatively opaque rigid tube embracing each of said light transmitting elements, and means securing one end of each of said tubes to said form, said tubes supporting said light transmitting elements upon said form and confining therein the rays of light passing therethrough to said object.

5
